United States Patent Office

Des. 219,597
Patented Dec. 29, 1970

219,597

CURRENT TRANSFORMER

John A. Smith, Rochester, N.H., assignor to General Electric Company, a corporation of New York

Filed Nov. 10, 1969, Ser. No. 20,012

Term of patent 14 years

Int. Cl. D13—02

U.S. Cl. D26—15

FIG. 1 is a top plan view of a current transformer showing my new design;

FIG. 2 is a front view of the transformer design, the other side being a mirror image;

FIG. 3 is a side view of the transformer design;

FIG. 4 is a bottom plan view; and

FIG. 5 is a perspective view thereof.

I claim:

The ornamental design for a current transformer, as shown and described.
